UNITED STATES PATENT OFFICE.

FREDERICK HACKMANN, OF MILWAUKEE, WISCONSIN, ASSIGNOR, BY
DIRECT AND MESNE ASSIGNMENTS, TO THE AUTOMATIC INDICATOR
COMPANY, OF SAME PLACE.

INDICATOR.

SPECIFICATION forming part of Letters Patent No. 616,417, dated December 20, 1898.

Application filed November 26, 1897. Serial No. 659,786. (No model.)

To all whom it may concern:

Be it known that I, FREDERICK HACKMANN, of Milwaukee, in the county of Milwaukee and State of Wisconsin, have invented a new and useful Improvement in Indicators, of which the following is a description, reference being had to the accompanying drawings, which are a part of this specification.

My invention has relation to improvements in indicators.

The invention is adapted for a variety of different uses—such, for instance, as fire-alarm indicators, hotel-annunciators, &c.

The primary object had in view is to provide an improved construction of device of the above character in which numbers or digits are printed on a movable slip of paper in contradistinction to marks or dashes printed on a movable slip of paper, as is now done in the most common form of fire-alarm indicators.

A further object resides in the provision of a construction which in the case of a fire-alarm apparatus, for instance is applicable to any existing system in which alarm-boxes are provided in connection with a make-and-break electrical circuit.

Furthermore, my invention contemplates as objects simplicity and cheapness of construction.

With the above and other incidental objects in view the invention consists of the devices and parts or their equivalents, as hereinafter more fully set forth.

In the accompanying drawings, Figure 1 is a side elevation with the pump and other parts in section. Fig. 2 is a plan view of the complete machine. Fig. 3 is a section on the line 3 3 of Fig. 2. Fig. 4 is a section on the line 4 4 of Fig. 1, and Fig. 5 is a section through the printing-roller.

Referring to the drawings, the numeral 6 indicates a base-plate provided at one end with binding-posts 7, to which are connected, respectively, the supply and return wires. (Not shown.)

Mounted upon the base-board is a metallic frame consisting of a base 8, provided at one end with an upwardly-extending member 9,

preferably of arch-shaped form. The base 8 is secured to the base-board by being screwed or otherwise suitably connected thereto.

Supported on the base 8 is an electromagnet 10. From the binding-posts 7 extend wires 11 and 12, leading to the respective coils of 55 the electromagnet. The armature 13 of the electromagnet is secured medially to a medial point of a pivoted lever 14. Near one end this lever has projecting laterally therefrom the pintles 15. The ends of these pintles 60 are pointed and turn in recesses formed in the ends of adjusting-screws 16, said screws passing through threaded openings in the side arms of the upwardly-extending arch-shaped portion 9 of the base 8. These screws 65 are provided at their outer ends with milled heads 17 for convenience in turning the same. The screws also carry jam-nuts 18, which are adapted to be turned against the side arms of the arch-shaped portion 9, so as to hold 70 the screws in adjusted position. Whenever it is desired to turn the screws for the purpose of adjusting the bearings, the jam-nuts, of course, are loosened. It is obvious that the farther inward the adjusting-screws are 75 turned the greater will be the power required to turn the lever on its pivot, and when the screws are turned outwardly the lever will turn more freely or with less power. The lever has depending from its pivotal end a rod 80 19, the lower end of which is engaged by one end of a coiled spring 20. To the opposite end of this coiled spring is connected a screw 21. This screw passes through a plain or unthreaded opening in a post or upright 22 and 85 is provided for a desired distance longitudinally with a groove 23. A pin 24 extends inwardly from the post and enters this groove. By this arrangement the screw is prevented from rotating. Nuts 25 25' engage the screw 90 on opposite sides of the post. The nut 25 is adapted to be turned so as to cause a longitudinal movement of the screw, and the nut 25' is adapted to be turned against the post when the desired adjustment of the screw is 95 obtained, thereby acting as a jam-nut and in connection with the nut 25 holding the screw against longitudinal movement after

proper adjustment of the same. By adjusting the screw 21 it is obvious that the tension of the spring 20 may be regulated, the function of said spring being to return the lever 5 to its normal position after said lever has been turned down on its pivot.

Mounted on the upper end of the post 22 is a curved or U-shaped arm 26. Between the upper and lower members of this arm extends 10 the end of the lever 14. Passing vertically through a threaded opening in said lever 14 is a screw 27. The upper end of this screw is provided with a milled head 28 for convenience in turning the same. This screw forms 15 an adjusting device, whereby the limit of the down movement of the lever is regulated, the lower end of the screw being adapted to contact with the lower member of the curved arm 26. A jam-nut 29 is adapted to turn on the 20 screw above the lever, and this jam-nut by being turned against the lever serves to hold the screw to adjusted position. The extent of the upward movement of the lever is regulated by means of a similar screw 30, which 25 turns in a threaded opening formed in the upper member of the curved arm 26, and with the end of which screw the upper side of the end of the lever is adapted to contact on the up movement of said end of the lever. 30 This screw is also provided with a milled head 31 for convenience in turning the same and carries thereon a jam-nut 32, adapted to be turned against the upper side of the upper member of the curved arm 26 in order to hold 35 the screw to adjusted position.

Extending outwardly from one side of a supplemental framework 33 is a pivot-pin 34. On this pin is mounted a rocking lever 35. One end of this rocking lever is provided with 40 an elongated slot 36, into which is adapted to extend a projecting pin 37 from the end of the lever 14. Mounted in the side pieces of the supplemental frame 33 is a shaft 38, which shaft has mounted fast thereon between the 45 side pieces of the supplemental frame a feed-roller 39. The shaft 38 has also mounted fast thereon adjacent to one end of the feed-roller 39 a cog-wheel 40. One of the ends of the shaft 38, which projects beyond the side of 50 the supplemental frame, has mounted thereon a ratchet-wheel 41. Pivoted at a medial point to the angularly-bent end 42 of one arm of the rocking lever 35 is a pawl 43. The upper end of this pawl engages the ratchet- 55 wheel, and to the lower end of the pawl is connected one end of the coiled spring 44. The opposite end of this coiled spring is connected to a projecting arm 45. From this construction it will be seen that as the end of 60 the lever 14 is forced downwardly it will throw the end of the rocking lever 35, to which the pawl 43 is connected, upwardly. This will cause the upper end of said pawl to engage a succeeding tooth of the ratchet-wheel, 65 so that the moment the end of the lever 14 is again raised the pawl will be returned to its normal position by the spring 44, and the

ratchet-wheel will thereby be turned the distance of one tooth, and will consequently rotate the shaft 38 and the drum and cog-wheel 70 mounted upon said shaft. The cog-wheel is held against backward rotation by means of a spring-dog 46, secured at its lower end to the base 8 and having its upper end engaging the teeth of the ratchet-wheel.

Mounted in elongated bearings 47, formed at the upper ends of extensions from the supplemental frame 33, is a shaft 48, the ends of this shaft being squared to prevent said shaft from turning in its bearings. On this shaft 80 is mounted a printing-wheel 49 and also loosely a cog-wheel 50 adjacent and fast to one side of the printing-wheel. This wheel is shown in the accompanying illustration of my invention as provided peripherally with a 85 series of numbers, which are in the present exemplification of my invention designed to run from "1" to "9." The numbers, if desired, may be formed upon a peripheral band 51, of rubber or other suitable yielding material, as 90 clearly shown in Fig. 5. It will also be seen from Fig. 5 that the wheel is chambered or hollow, and in this chambered or hollowed-out portion is arranged a clock-spring 52. One end of this spring is secured to the shaft 48 and the 95 other end to the inside of the wheel. When the wheel is turned in one direction, it is obvious that the spring is wound up tightly on the shaft, and the moment the wheel is released after being turned in such direction the 100 unwinding of the spring returns the wheel to its normal position. The normal position of the wheel is such that the number "1" is in position to make the first imprint, and said position is always secured by means of a pin 53, 105 which enters a recess 54 in the printing-wheel, as clearly shown in Fig. 4. The end of the pin within this recess is formed with an enlargement or head 55, and between this head and the inner wall of the recess 54 is confined a 110 coiled spring 56, which spring exerts a pressure outwardly on the pin and normally holds said pin outwardly, so as to contact with a part of the framework, and constitutes said pin a stop for regulating the extent to which 115 the printing-wheel is rotated backward, or, in other words, after the spring 52 has uncoiled to permit the printing-wheel to rotate backward only so far as to bring the number "1" again in position to make the first 120 imprint. It will be understood that even at this point there is some tension on the spring 52, as it is not fully unwound. If at any time it is desired to still further increase the tension of the printing-wheel 49, the pin 53 can be 125 pushed inwardly by the finger or otherwise against the action of the coiled spring 56, so as to extend far enough into the recess 54 as to clear the framework. The wheel can then be given an additional turn or turns, whereby 130 it is obvious that the tension of spring 52 is increased.

The numeral 57 indicates a yoke which has extending from one end thereof an arm 58.

The end of this arm is formed with an eye 59, in which is fast a pin 60. The ends of this pin are pointed and fit in recesses formed in the ends of screws 61 61, said screws being 5 provided upon their outer ends with milled heads 62 for convenience in turning the same. The screws pass through threaded openings in an angular bracket 63, and adapted to turn upon the screws are jam-nuts 64, which may 10 be made to bear firmly against the adjacent portions of the bracket, and thereby hold the screws firm to adjusted position. By providing these adjustable bearing-screws the yoke 51 may be made to turn with more or less 15 freedom, as desired. The side bars of the yoke 57 are provided with elongated slots 65, which receive the ends of the shaft 48. One of these side members is extended, as indicated at 66, and the extremity of this extension is formed with an elongated slot 67, which is adapted to receive the pin 37, projecting from the end of the lever 14.

Extending up from the base 8 is a post 68, which may be formed or provided with a U-shaped portion 69, and extending up from this U-shaped portion is a bifurcated arm 70, the furcate parts of which are formed at their upper ends with bearings 71. Mounted in these bearings is a shaft 72, which shaft carries 25 an inking-roller 73, which roller contacts with the periphery of the printing-wheel 49, so as to continually supply ink to the type or numbers on said printing-wheel. Mounted in bearings just in advance of the feed-roller 30 39 is another grooved roller 74, which grooved roller is in close proximity to the periphery of the feed-roller. Near one end of the base-board 6 are secured uprights 75, the upper ends of said uprights being provided with 35 40 openings which form bearings for the journals of a roller 76. This roller has radiating from opposite ends thereof the arms 77.

The numeral 78 indicates the strip of paper upon which the imprint of the printing-wheel 45 is to be made, said paper being wound upon the roller 76, as clearly shown in Fig. 1, and being confined between the radiating arms 77. The strip is then extended over the feed-roller 39, thence between said feed-roller and 50 the grooved roller 74, as clearly shown. The grooved roller therefore serves to keep the strip of paper in engagement with the periphery of the feed-roller.

Secured to an arm 79, extending from the 55 supplemental frame 33, is the cylinder of an air-pump 80. This cylinder is provided in its bottom with a valve-opening 81, which is controlled by means of a loose ball-valve 82. Within the cylinder works a piston 83, and 60 pivotally connected to this piston is the lower end of a stem 84. This stem passes through an opening in a screw-cap adjusted to the upper end of the cylinder, and the upper end of the stem has pivotally connected thereto 65 a rocking lever 85. The inner end of this rocking lever is pivotally connected to a yoke 86, the downwardly-extending arms of said

yoke straddling the printing-wheel 49 and being bent into hook form to engage under the ends of the shaft 48 of said printing-wheel. The pivot of this rocking lever consists of a transverse pin 87, the ends of which pin are received in recesses formed in the ends of screws 88, said screws passing through threaded openings in opposite portions of an angle-arm 89, secured to and extending upwardly from the supplemental frame 33. These screws are also provided on their outer ends with milled heads 90 for convenience in turning the same, and have also turning thereon jam-nuts 91, which serve to hold the screws firmly to adjusted position.

The above being a description of the parts of my invention, its operation will now be explained. For instance, if it is supposed that it is used in connection and in circuit with an electrical fire-alarm system the indicator is located at a suitable point where it is desired the alarm should be recorded—as, for instance, at a police-station. If now an alarm 90 is turned at any particular box by a person properly manipulating the turn-in lever of the box, so as to produce a make-and-break current, the electricity passing over the line-wire will be conducted to either of the binding-posts 7, and from thence by either of the wires 11 or 12 (in accordance with which wire is the supply-wire) to the electromagnet. As this magnet is energized the armature is drawn toward and to the cores of the magnet. Inasmuch as the armature is connected to the lever 14, of course said lever is caused 100 to turn on its pivot, causing the opposite end thereof to descend. With this descent of the end of the lever 14 the rocking lever 35 is 105 turned on its pivot, so as to move the dog 43 to a point to engage the next tooth of the ratchet-wheel 41. At the same time the extended arm 66 of the yoke 57 is brought 110 downwardly, so as to cause the printing-wheel to descend and at the same time the teeth of the cog-wheel 50 to engage the teeth of the cog-wheel 40. The descent of the printing-wheel causes the imprint of the number "1" 115 on the strip of paper 78, which paper passes between said printing-wheel and the feed-wheel 39. With the down movement of the printing-wheel also the yoke 86 is pulled downwardly, and this causes a turning of the rocking lever 85 and a consequent uplifting of the piston-stem 84 and its piston 83 and at the same time a raising of the valve 82 to permit air to enter the cylinder 80. At this time the current is broken, and the moment this occurs the armature 13 is no longer attracted to 125 the electromagnet, and consequently the lever 14 is free to return to its normal position. This has the effect at the same time of rocking the lever 35, so as to return to its normal position, and causing the dog carried thereby 130 to rotate the ratchet-wheel 41 the distance of one tooth. As the cog-wheel 40 is carried on the same shaft with the ratchet-wheel 41, said cog-wheel 40 is also thereby rotated, and the

roller 39, which is likewise mounted on the same shaft with the cog-wheel 40 and ratchet-wheel 41, is also rotated. Inasmuch, also, as the teeth of the cog-wheel 40 engage the teeth 5 of the cog-wheel 50, said cog-wheel 50 is rotated a sufficient distance in the opposite direction to cause the rotation of the printing-wheel, which is fast thereto, the rotation of said printing-wheel being sufficient to bring 10 the next number on its periphery in position to make the succeeding imprint. The rotation of the feed-roller 39, as just explained, furthermore causes the strip of paper 78 to be fed forwardly a sufficient distance to present 15 a clear space for the imprint of the next number. With the uplifting of the armature the yoke 57 is also free to turn back to its normal position. This turning back of said yoke is just sufficient to raise the printing-roller clear 20 of the feed-roller, so as to allow for the passage or forward movement of the strip of paper. It is not raised, however, by said yoke sufficiently high to clear the teeth of the cog-wheel 50 from the teeth of the cog-wheel 40. When, 25 however, there is a period of rest between the makes and breaks, the cog-wheel 50 is raised sufficiently high to clear the teeth of the cog-wheel 40 by reason of the uplifting of the yoke 86, the arms of which engage the shaft 30 48 and are moved upwardly the moment the yoke 57 has been turned, as hereinbefore described. It will be noticed that the slots 65 in the arms of the yoke 57 are somewhat wider than the diameter of the shaft 48, so that after 35 the yoke 57 has completed its full movement the yoke 86 is still permitted to move upwardly far enough to bring the shaft 48 into contact with the upper edges of the slots 65, and this distance is sufficient to clear the 40 teeth of the cog-wheel 50 from the teeth of the cog-wheel 40. The yoke 86 is caused to move upwardly gradually by the rocking lever 85 and the connection between said rocking lever and the piston 83 of the air-pump. 45 As said rocking-lever 85 is turned on its pivot the piston is caused to slowly descend, being resisted by the air beneath the same, which is permitted to escape slowly through the valve-opening of the cylinder, owing to the 50 loose fit of the ball-valve 82. By the time the piston 83 has made its full descent the cog-wheel 50 is raised to its highest extent, which is, as before stated, to such a point as to clear the teeth of the respective cog-wheels. 55 The moment this clearance occurs the coiled spring 52 within the printing-wheel causes a reverse rotation of said printing-wheel to such an extent as to again bring the number "1" on the under side of the printing-wheel to such 60 position as to make the next succeeding imprint, it being understood that this reverse rotation of the printing-wheel is limited by the stop-pin 53.

In the use of my invention in a fire-alarm system it will be supposed that an alarm is turned in from box "23." The moment the current is made or completed to the indicator

and the printing of the number "1" is caused on the strip of paper the current is then again broken and quickly completed again before the teeth of the cog-wheels 50 and 40 have had a chance to disengage and causing the printing of the number "2." After the number "2" is struck there is then a period of rest in the make-and-break current, which allows sufficient time for the printing-wheel to ascend far enough to disengage the teeth of the cogs 50 and 40. The moment this disengagement takes place the coiled spring 52 unwinds and returns the printing-wheel to a position in which the number "1" is again on the under side of the roller directly above the strip of paper and in line to make an imprint. The period of cessation of the make and break is followed by three rapid make-and-break currents, which respectively cause the printing of the numbers "1," "2," and "3," and the printing of this last number "3" is followed by another period of rest, which allows of the disengagement of the teeth of the two cog-wheels and the return of the printing-wheel to its normal position. The alarm is read by reading the last figure after "1" as often as the number "1" occurs. For instance, on the strip of paper shown in Fig. 2 the numbers "1 2 1 2 3" are shown. The last figure following the first "1" is "2," and the last figure following the second "1" is "3," thus indicating that the alarm is "23." This system of reading the alarm is true with respect to any alarm which may be turned in.

While I have described certain details of construction in the foregoing description, yet I do not wish to be understood as limiting myself to the specific construction of many of the parts hereinbefore described, inasmuch as many of such parts may be changed or modified without materially departing from the spirit and scope of my invention. I also do not wish to be understood as restricting myself to a printing-wheel having numbers or digits on the periphery thereof, inasmuch as any other suitable characters may be employed to suit the purposes to which the indicator is applied.

What I claim as my invention is—

1. In an electrical indicator, the combination, of an electrical circuit, a lever adapted to be turned from its normal position on each completion of the circuit, a printing-wheel, means for feeding paper, or other suitable material to be printed upon, to the wheel, mechanism between the printing-wheel and the lever, said mechanism adapted, as the lever is turned from its normal position, to cause the printing-wheel to contact with and make an imprint upon the strip of paper, or other suitable material, and on the breaking of the current to cause the printing-wheel to revolve, and the feeding mechanism to feed the paper forward, the revolving of the printing-wheel causing the next succeeding number or character thereon to be brought and held in place, when followed by a subsequent instant com-

pletion of the current, and mechanism adapted, during a cessation of the electrical makes and breaks, to cause the printing-wheel to return to its normal position for printing its initial number or character.

- 5 2. In an electrical indicator, the combination, of an electrical circuit, a lever adapted to be turned from its normal position on each completion of the circuit, a printing-wheel, a feed-wheel adjacent thereto, mechanism between the wheels and the lever, said mechanism adapted as the lever is turned from its normal position to cause the printing-wheel to contact with and make an imprint on a strip of suitable material between the wheels, and on the breaking of the current to cause the printing-wheel to move out of contact with the feeding-wheel, and the two wheels to revolve, and the paper thereby fed forward, the 15 revolving of the printing-wheel causing the next succeeding number or character thereon to be brought and held in place when followed by a subsequent instant completion of the current, and mechanism adapted, during a cessation of the electrical makes and breaks, to cause the printing-wheel to return to its normal position for printing its initial number or character.
- 20 3. In an electrical indicator, the combination, of an electrical circuit, an electromagnet within the circuit, an armature for the electromagnet, a pivoted lever secured to said armature, a printing-wheel, a feed-wheel adjacent thereto, mechanism between the wheels and the lever, said mechanism adapted, as the lever is turned from its normal position by the completion of the current, to cause the printing-wheel to engage the feed-wheel and make an impression on a strip of suitable material passed between the wheels, and on the breaking of the current to throw the printing-wheel out of engagement with the feeding-wheel and to also cause the two wheels to revolve and the strip of material to be fed forward, the revolving of the printing-wheel causing the next succeeding number or character thereon to be brought into position for printing, and to hold the wheel at such position whenever the first make and break is 45 followed by a subsequent instant completion of the current, and mechanism adapted during a cessation of the electrical makes and breaks to cause the printing-wheel to return to its normal position for printing its initial number or character.
- 50 4. In an indicator, the combination, of an operating-lever, means for turning said lever from its normal position, a shaft, a feed-wheel mounted on said shaft, a cog-wheel and a ratchet-wheel also mounted on said shaft, another shaft mounted movably in bearings, a printing-wheel and a cog-wheel mounted on said shaft, a rocking lever having one end connected to the operating-lever, a dog pivotally connected to the other end of the lever and adapted to engage the teeth of the ratchet-wheel, and mechanism between the 55 ends of the operating-lever and the printing-wheel, said mechanism adapted as the operating-lever is turned in one direction to cause the printing-wheel to engage the surface of the feed-wheel and the two cog-wheels to mesh, and when operated in the opposite direction adapted to throw the printing-wheel and the feed-wheel out of engagement and also the two cog-wheels out of engagement, and mechanism adapted during a cessation of the movements of the operating-lever to cause the printing-wheel to return to its normal position.

55 5. In an indicator, the combination, of an operating-lever adapted to be turned from its normal position, a shaft, a feed-wheel mounted on said shaft, a cog-wheel and a ratchet-wheel also mounted on said shaft, another shaft mounted movably in bearings, a printing-wheel and a cog-wheel also mounted on said shaft, a rocking lever having one end connected to the operating-lever; a dog pivotally connected to the other end of the rocking lever and adapted to engage the teeth of the ratchet-wheel, mechanism between the end of the operating-lever and the printing-wheel, 60 said mechanism adapted as the operating-lever is turned in one direction to cause the printing-wheel to engage the surface of the feed-wheel and the two cog-wheels to mesh, and when operated in the opposite direction adapted to throw the printing-wheel and the feed-wheel out of engagement and also the two cog-wheels out of engagement, and mechanism adapted during a cessation of the movements of the operating-lever to cause the printing-wheel to return to its normal position.

60 6. In an indicator, the combination, of an operating-lever adapted to be turned from its normal position, a shaft, a feed-wheel mounted on said shaft, a cog-wheel and a ratchet-wheel also mounted on said shaft, another shaft mounted movably in bearings, a printing-wheel and a cog-wheel also mounted on said shaft, a rocking lever having one end connected to the operating-lever, a dog pivotally connected to the other end of the lever and adapted to engage the teeth of the ratchet-wheel, and a pivoted yoke having its arms provided with elongated slots adapted to receive the ends of the shaft of the printing-wheel, one end of said yoke being extended so as to engage the end of the operating-lever.

65 7. In an indicator, the combination, of an operating-lever, means for turning said lever from its normal position, a shaft, a feed-wheel mounted on said shaft, a cog-wheel and a ratchet-wheel also mounted on said shaft, another shaft mounted movably in bearings, a printing-wheel and a cog-wheel mounted on said shaft, a rocking lever having one end connected to the operating-lever, a dog pivotally connected to the other end of the lever and adapted to engage the teeth of the ratchet-wheel, a pivoted yoke having its arms provided with elongated slots adapted to receive the ends of the shaft of the printing-wheel, 70 said slots being wider than the diameter of the ends of the shaft, and one of said arms being extended so as to engage the end of

the end of the operating-lever and the printing-wheel, said mechanism adapted as the operating-lever is turned on its pivot in one direction to cause the printing-wheel to engage the surface of the feed-wheel and the two cog-wheels to mesh, and when operated in the opposite direction adapted to throw the printing-wheel and the feed-wheel out of engagement and the two cog-wheels also out of engagement.

75 8. In an indicator, the combination, of an operating-lever adapted to be turned from its normal position, a shaft, a feed-wheel mounted on said shaft, a cog-wheel and a ratchet-wheel also mounted on said shaft, another shaft mounted movably in bearings, a printing-wheel, and a cog-wheel also mounted on said shaft, a rocking lever having one end connected to the operating-lever; a dog pivotally connected to the other end of the rocking lever and adapted to engage the teeth of the ratchet-wheel, mechanism between the end of the operating-lever and the printing-wheel, 80 said mechanism adapted as the operating-lever is turned in one direction to cause the printing-wheel to engage the surface of the feed-wheel and the two cog-wheels to mesh, and when operated in the opposite direction adapted to throw the printing-wheel and the feed-wheel out of engagement and also the two cog-wheels out of engagement, and mechanism adapted during a cessation of the movements of the operating-lever to cause the printing-wheel to return to its normal position.

85 9. In an indicator, the combination, of an operating-lever adapted to be turned from its normal position, a shaft, a feed-wheel mounted on said shaft, a cog-wheel and a ratchet-wheel also mounted on said shaft, another shaft mounted movably in bearings, a printing-wheel and a cog-wheel also mounted on said shaft, a rocking lever having one end connected to the operating-lever, a dog pivotally connected to the other end of the lever and adapted to engage the teeth of the ratchet-wheel, and a pivoted yoke having its arms provided with elongated slots adapted to receive the ends of the shaft of the printing-wheel, one end of said yoke being extended so as to engage the end of the operating-lever.

90 10. In an indicator, the combination, of an operating-lever, means for turning said lever from its normal position, a shaft, a feed-wheel mounted on said shaft, a cog-wheel and a ratchet-wheel also mounted on said shaft, another shaft mounted movably in bearings, a printing-wheel and a cog-wheel mounted on said shaft, a rocking lever having one end connected to the operating-lever, a dog pivotally connected to the other end of the lever and adapted to engage the teeth of the ratchet-wheel, a pivoted yoke having its arms provided with elongated slots adapted to receive the ends of the shaft of the printing-wheel, 95 said slots being wider than the diameter of the ends of the shaft, and one of said arms being extended so as to engage the end of

the operating-lever, and a device also engaging the ends of the shaft of the printing-wheel, and adapted to pull said wheel a greater distance away from the feed-wheel than said printing-wheel is pulled by the yoke, the latter augmented movement of the printing-wheel adapted to cause a disengagement of the teeth of the cogs.

8. In an indicator, the combination, of an operating-lever, means for turning said lever from its normal position, a shaft, a feed-wheel mounted on said shaft, a cog-wheel and a ratchet-wheel also mounted on said shaft, another shaft movable in bearings, a printing-wheel and a cog-wheel mounted on said shaft, a rocking lever having one end connected to the operating-lever, a dog pivotally connected to the other end of the lever and adapted to engage the teeth of the ratchet-wheel, a pivoted yoke having its arms provided with elongated slots adapted to receive the ends of the shaft of the printing-wheel, said slots being wider than the diameter of the ends of the shaft, and one of said arms being extended so as to engage the end of the operating-lever, a yoke also engaging the ends of the shaft of the printing-wheel, a lever to which said yoke is connected, and means for operating said lever.

9. In an indicator, the combination, of an operating-lever, means for turning said lever from its normal position, a shaft, a feed-wheel mounted on said shaft, a cog-wheel and a ratchet-wheel also mounted on said shaft, another shaft movable in bearings, a printing-wheel and a cog-wheel mounted on said shaft, a rocking lever having one end connected to the operating-lever, a dog pivotally connected to the other end of the lever and adapted to engage the teeth of the ratchet-wheel, a pivoted yoke having its arms provided with elongated slots adapted to receive the ends of the shaft of the printing-wheel, said slots being wider than the diameter of the ends of the shaft, and one of said arms of the yoke being extended so as to engage the end of the operating-lever, another yoke also engaging the ends of the shaft of the printing-wheel, a lever

to which said yoke is connected, and an air-pump having the piston-stem thereof connected to the end of the last-referred-to lever. 50

10. In an indicator, the combination, of a printing-wheel, a shaft on which said wheel is mounted, a spring connected at one end to said shaft, and having its opposite end connected to the wheel, and a contact-pin extending laterally from a recess of the printing-wheel, and adapted when the wheel is turned in a direction to wind the spring to be pressed inwardly into the recess in order 60 to clear a fixed point or stop of a framework. 55

11. In an electrical indicator, the combination, of an electrical circuit, a lever adapted to be turned from its normal position on each completion of the circuit, a printing-wheel, a feed-wheel adjacent thereto, another wheel in advance of the feed-wheel, a roller, a strip of material wound on said roller and extended between the feed-wheel and the printing-wheel and also between the feed-wheel and the roller in advance of said feed-wheel, mechanism between the feed-wheel and the printing-wheel and the lever, said mechanism adapted as the lever is turned from its normal position to cause the printing-wheel to descend and make an imprint on the strip of material passing between the wheel, and on the breaking of the current to cause the printing-wheel to ascend and the two wheels to revolve and the paper to be fed forward, the 80 revolving of the printing-wheel causing the next succeeding number or character thereon to be brought and held in place whenever followed by an instant completion of the current, and mechanism adapted, during a cessation 85 of the electrical makes and breaks, to cause the printing-wheel to return to its normal position to print the initial number or character on the strip of material to be printed upon.

In testimony whereof I affix my signature 90 in presence of two witnesses.

FREDERICK HACKMANN.
